UNITED STATES PATENT OFFICE.

JAMES BROWN, OF PAWTUCKET, RHODE ISLAND.

DESIGN FOR A THREAD-GUIDE.

SPECIFICATION forming part of Design No. 29,923, dated January 3, 1899.

Application filed December 1, 1898. Serial No. 698,024. Term of patent 3½ years.

To all whom it may concern:

Be it known that I, JAMES BROWN, of the city of Pawtucket, in the county of Providence and State of Rhode Island, have invented and produced a new and original Design for a Thread-Guide for Spinning-Machines, of which the following is a specification, reference being had to the accompanying drawings, forming part thereof.

Figure 1 is a front elevation of my design. Fig. 2 is an end view of the same.

The essential feature of my design consists of a plain round wire W, bent in the form as represented in Figs. 1 and 2, respectively. In referring to Fig. 1 said wire has its top portion bent circularly in the form of a loop, as shown by letter l, from whence it continues downwardly and straight to a point o, then turning at a right angle with the vertical portion m and taking a horizontal course forward

for a short distance to a point r, where it again turns downward and straight to a point t, and the three courses m, p, and s are in the same plane or alinement with each other. From the point t the wire is bent at a right angle with the aforesaid courses m, p, and s, respectively, and leads horizontally to a point v, then taking a downward semicircular turn, and finally leading parallel with the course u to a point w beneath the vertical portion s.

Having described my invention, what I claim as new, and desire to secure by Letters Patent, is—

The design for a thread-guide, as herein shown and described.

JAMES BROWN.
